UNITED STATES PATENT OFFICE.

LAFAYETTE F. CRAWFORD, OF DENVER, COLORADO.

FOUNTAIN-PEN.

No. 874,738.

Specification of Letters Patent.

Patented Dec. 24, 1907.

Application filed July 3, 1906. Serial No. 324,686.

To all whom it may concern:

Be it known that I, LAFAYETTE F. CRAWFORD, a citizen of the United States, residing at Denver, in the county of Denver and State 5 of Colorado, have invented certain new and useful Improvements in Fountain-Pens, of which the following is a specification.

My invention relates to an improvement in fountain pens, and more particularly the 10 means for filling the pen with ink.

The object is to render it unnecessary to remove the point in order to fill or re-fill the pen whereby greatly lessening the difficulty and facilitating the process of refilling a fountain pen.

With these objects in view my invention consists in certain novel features of construction and combinations of parts which will be hereinafter described and pointed out in the 20 claims.

In the accompanying drawings:—Figure 1 is a view in side elevation with parts broken away and in section to show the internal construction. Fig. 2 is an enlarged sectional 25 view through the plunger and cap. Fig. 3 is a view showing a form of key. Fig. 4 is a view showing a modified form of key applied to the pen. Fig. 5 is a view similar to Fig. 1, showing this modified form of key screwed to 30 the plunger.

A, represents the barrel of the pen holder, 1 is the pen section and 2 the pen point.

The plunger for filling comprises a head 4 and a stem, the outer portion 5 being threaded and the inner portion 6, preferably without threads, a shoulder 7 being formed between the head and stem. A washer 8 of leather or other soft material is secured to the head by a screw or equivalent device 9, this 40 washer being of a size to snugly fit the bore of the barrel in order to create the required suction therein as the plunger is pulled out in the act of filling the barrel of the holder. A second washer 10, is mounted on the threadless 45 portion 6, of the stem against the shoulder 7, in position to strike the flange 11 at the outer end of the barrel, its function being to prevent the ink from leaking out at that end, it affording an air and ink tight closure or stopper 50 for the barrel. The usual cap 12 at the outer end of the pen holder, instead of screwing directly upon the end of the holder is adapted to screw upon the threaded end 5 of the plunger, which end protrudes through the 55 outer end of the pen holder when in its normal position after the pen has been filled and

the screwing of the cap upon this threaded end of the plunger draws it tightly in place and the washer 10 is compressed between the shoulder 7 on the plunger and the flange 11 at 60 the outer end of the holder thus making a tight closure at that point.

The plunger is operated by any approved form of removable key, two of which I have illustrated in the drawings, one is a plain, 65 straight rod 13 with a head 14 on one end, and a screw-thread 19, on the other, which screws into the threaded orifice 15 in the stem of the plunger whereby it may readily be applied or removed. The other form of 70 key is preferably held frictionally upon the end 16 of the pen holder by the spiral end 17 which snugly embraces the end of the holder. This key is provided with a joint 18, in the center whereby it may be folded and at its 75 outer end is provided with a screw-thread to screw into the orifice in the plunger. This form of key has a secondary function of providing a pocket fastener when folded to hook the holder in the vest-pocket, against accidental loss or displacement.

The operation of filling the pen is perfectly obvious. The cap 12 is first unscrewed and the key is screwed into the orifice in the plunger, and the latter is forced 85 down to the lower end of the pen holder, the pen point without the necessity of being removed, is thereupon inserted in the ink, and the plunger is drawn upwardly, thus by suction filling the barrel of the pen holder. 90 When pulled as far as it will go, the key is removed, and the cap is replaced by screwing it to the threads of the stem whereby the pen is ready for use. In this way the filling of the pen is not at all troublesome or difficult 95 and it may be done without taking the pen apart or removing the pen point or soiling the fingers in the slightest degree.

Slight additional changes might be resorted to in the form and arrangement of the 100 several parts described without departing from the spirit and scope of my invention, and hence I do not wish to limit myself to the exact construction herein set forth, but:

Having fully described my invention, 105 what I claim as new and desire to secure by Letters Patent, is:

1. A fountain pen comprising a pen holder and having an ink filling plunger fitted to the bore of the holder, said plunger comprising a 110 head and threaded stem with a shoulder therebetween, a flexible washer mounted on

- the stem against the shoulder and the holder having an internal flange at its outer end, between which and the shoulder on the plunger the washer is adapted to be held and compressed, and a removable cap adapted to be screwed to the stem of the plunger whereby the plunger and cap are held in position and the washer is compressed to form an air and ink tight joint at the end of the pen.
- 10 2. In a fountain pen, the combination with a barrel and a plunger having a threaded stem of sufficient length to protrude through an end of the barrel when in one of its extreme positions, of a key adapted to be removably secured to the protruding end of the plunger and a cap constructed and adapted to screw upon the protruding end of the plunger when the key is removed whereby to fasten the plunger and cap in position.
- 15 3. In a fountain pen, the combination with a barrel and a plunger the barrel having an orifice at one end and the plunger provided with a threaded stem adapted to protrude through said orifice, said stem having an orifice which extends only partly through it and a key adapted to be removably secured in said orifice in the stem.
4. In a fountain pen, the combination with the barrel, of a key secured to a part of the pen and normally lying alongside the latter whereby space is formed between the pen and key to receive the pocket for fastening the pen to the pocket.
- 20 5. In a fountain pen, the combination with

the barrel, of a key secured to a part of the pen and normally lying alongside the latter whereby space is formed between the pen and key to receive the pocket for fastening the pen to the pocket, said key having a joint formed therein whereby it may be folded.

6. In a fountain pen, the combination with the barrel, of a key secured to a part of the pen and normally lying alongside the latter whereby space is formed between the pen and key to receive the pocket for fastening the pen to the pocket, said key being frictionally held upon a part of the pen holder.

7. In a fountain pen, the combination with the barrel, of a key normally lying alongside the barrel whereby space is formed between the pen and key to receive the pocket for fastening the pen to the pocket, said key being foldable and frictionally and adjustably held upon a section of the pen holder.

8. A combined piston-rod and holding clip for use with fountain pens screw-threaded at one end and provided at the other with yielding means for adjustably attaching it to a part of the pen when detached from the filling piston-head, substantially as described.

In testimony whereof I affix my signature in presence of two witnesses.

LAFAYETTE F. CRAWFORD.
